UNITED STATES PATENT OFFICE.

WILSON C. BERGER, OF CANTON, OHIO.

METAL ROOFING.

SPECIFICATION forming part of Letters Patent No. 399,004, dated March 5, 1889.

Application filed January 10, 1889. Serial No. 296,015. (No model.)

To all whom it may concern:

Be it known that I, WILSON C. BERGER, a citizen of the United States, and a resident of Canton, in the county of Stark and State of Ohio, have invented certain new and useful Improvements in Metal Roofing; and I do hereby declare that the following is a full, clear, and exact description of the same, reference being had to the annexed drawings, making a part of this specification, in which—

Figure 1 is a view showing the roof in different stages of completion. Fig. 2 is a longitudinal section showing the flanges in an upright position. Fig. 3 is a view showing one of the seams formed and another seam partly formed. Fig. 4 is an enlarged view of a portion of the sheets, showing the lips cut into the top edge of the tongued-up portion *a* and into the cleat or anchor and turned down.

20 The present invention has relation to metal roofing; and its nature consists in the different parts and combination of parts, herein-after described, and particularly pointed out in the claims.

25 Similar letters of reference indicate corresponding parts in all the figures of the drawings.

In the accompanying drawings, A represents the sheets, which are constructed of the desired length, one edge of said sheets being provided with the tongued-up portion *a*, the opposite edge being provided with the tongued-up portion *b*. In use a strip or sheet, A, is placed on the roof, when the anchors B are placed against the tongued-up portion *a* and securely nailed to the sheeting of the roof. The portion of the cleat or anchor B which abuts against the tongued-up portion *a* extends to the top or upper edge of said portion.

40 For the purpose of securely locking the anchors the top or upper end of said anchors and the upper edge of the tongued-up portion

a are cut or notched, as shown at C, and the portion or lips so formed are bent or folded down, as illustrated in the drawings, thereby 45 securely and firmly locking the anchors to the sheets. The tongued-up portion *a* extends a short distance above the top of the tongued-up portion *b*, and the portion so extending is bent or folded over the tongued-up portion *b*, 50 thereby carrying with it the cleat or anchor B, thus forming a water-tight joint.

It will be seen that the lips C may be cut or formed at any point between the top of the tongued-up portion *a* and the top of the 55 tongued-up portion *b*, said lips C being cut through the anchors and tongued-up portion *a* and both of said lips folded down.

Having fully described my invention, what I claim, and desire to secure by Letters Patent, is—

1. The combination of the sheets A, provided with the tongued-up portions *a* and *b*, the lips C, formed in the tongued-up portion *a* and the anchors B and said lips folded over 65 each other, and the tongued-up portion *a* extending above the tongued-up portion *b*, bent or folded over the tongued-up portion *b*, together with the anchors B and lips C, substantially as and for the purpose set forth. 70

2. The sheets A, provided with the tongued-up portions *a* and *b*, the anchor B, and the lips C, formed in the anchors B and the tongued-up portion *a*, said lips cut opposite to each other and both of said lips bent down, substantially 75 as and for the purpose set forth.

In testimony that I claim the above I have hereunto subscribed my name in the presence of two witnesses.

WILSON C. BERGER.
